UNITED STATES PATENT OFFICE.

JOHN K. HAWKINS, OF MORRISTOWN, TENNESSEE.

ACETYLENE-GAS GENERATOR.

1,405,031.

Specification of Letters Patent. Patented Jan. 31, 1922.

Application filed January 9, 1920. Serial No. 350,375.

To all whom it may concern:

Be it known that I, JOHN K. HAWKINS, a citizen of the United States, residing at Morristown, in the county of Hamblen and 5 State of Tennessee, have invented a new and useful Acetylene-Gas Generator, of which the following is a specification.

The device forming the subject matter of this application is an acetylene gas generator, and one object of the invention is to provide a device of the kind mentioned 10 which can be charged and recharged readily, at will.

Another object of the invention is to provide novel means whereby an excessive or 15 dangerous pressure may be relieved without depleting the water supply.

It is within the province of the disclosure 20 to improve generally and to enhance the utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in the precise embodiment of the invention 30 shown can be made without departing from the spirit of the invention.

In the accompanying drawings:—

Figure 1 shows in vertical section, a device 35 constructed in accordance with the invention; and Figure 2 is a section taken approximately on the line 2—2 of Figure 1.

The device forming the subject matter of this application includes a tank 1 in which a bell 2 is inverted, the bell being provided 40 on its top with handles 3. A retainer 4, preferably in the form of a rod, extends across the tank 1 and is removably mounted therein, the retainer passing through the handles 3. Obviously, the retainer constitutes 45 a means whereby the bell 2 will be prevented from rising, as the gas pressure therein accumulates. The bell 2 may be supported on legs 6 and is provided at its top with a cock 5. The cock 5 may be used 50 to let out air from the bell when the bell is placed in the tank 1.

The invention comprises a plurality of U-shaped supports 7 extended downwardly within the tank 1 and upwardly within the 55 bell 2, the outer portions of the supports 7 being received in guides 8 on the tank 1.

The supports 7 include inwardly projecting arms 9 connected as shown at 10 to carbide containers 11. The arm 9 has an upstanding finger 12 received in eyes 14 on a carbide 60 container 15, the carbide containers 15 and 11 being disposed, preferably, in groups of three. There may be as many or as few of these groups as occasion may demand. Spring actuated latches 16 are mounted in 65 the wall of the tank 1 and cooperate with the supports 7 to uphold the carbide containers 15 and 11. A single central container 20 may be supplied, the same being carried by a support 21 constructed like the 70 supports 7. The containers 20, 15 and 11 are provided with openings 22, so located, vertically, that, preferably, the water will enter one container at a time.

The numeral 17 denotes a service pipe 75 extended downwardly on the outside of the tank 1 and into the tank, below the bell 2, the service pipe 17 having an upstanding end 18 located within the bell and provided with a receiving head 19 through which the 80 gas enters. The service pipe 17 is controlled by a valve 23. A branch 24 leads from the service pipe 17 and communicates with an exhaust pipe 25. A valve 26 is located in the branch 24, between the vertical portion 85 of the service pipe 17 and the exhaust pipe 25. An upright receptacle 27 is located in the tank 1, between the tank and the bell 2, and is secured to the tank. The receptacle 27 is open at its bottom, the lower end of 90 the exhaust pipe 25 entering the top of the receptacle. The numeral 28 denotes an inverted U-shaped pipe, one arm of which extends upwardly into the receptacle 27, the other end of which extends upwardly within 95 the bell 2. The pipe 28 may be supported in any desired way, as indicated at 29.

In practical operation, the water rises in the bell 2 due to the head between the bell 2 and the tank 1. The water enters the 100 containers 11, 15 and 20, one after another, through the openings 22. As the gas is generated within the bell 2, the water is forced downwardly and the water rises between the tank 1 and the bell 2 until the gas 105 has been used to such an extent as to cause the water to rise again in the bell. Under ordinary working conditions, the gas passes by way of the head 19 into the part 18 of the service pipe 17 and passing the valve 110 23, which is open, flows to the point of use. If at any time the operator should desire to

lessen the pressure of gas in the bell 2, this can be accomplished by opening the valve 26, under which circumstances, the gas will flow by way of the branch 24 into the exhaust pipe 25. Should an undue pressure be created within the bell 2, the water will be forced downwardly and will rise between the tank 1 and the bell 2, some of the water along with the gas, flowing through the inverted U-shaped pipe 28. The water thus discharged, is received by the receptacle 27 and is directed back into the space between the tank 1 and the bell 2, the gas being trapped in the receptacle 27, and flowing away through the exhaust pipe. The device is so constructed, owing to the foregoing arrangement of parts, that dangerous pressure will be relieved before the machine can explode and before damage of any other kind results.

The retainer 4 may be withdrawn, thus setting the bell 2 free, so that it can be removed. The supports 7 are raised until the holes 22 in the carbide containers are above the normal water level, the containers being lifted off separately for filling. When the service valve 23 is closed, the gas in the bell holds the water down away from the openings 22 in the carbide containers, until the gas pressure is relieved. The water level is held down by gas pressure, until all the carbide in one can is exhausted, and then the water rises and enters another can.

Ordinarily, two groups of the containers 11-15 are lowered at once, so that the six holes 22 in the six containers of the two groups will admit water one after the other as the water rises. The central carbide container 20 is used in emergency, when, for instance, all of the other containers have been exhausted after night fall and the light fails. When all of the containers 11-15-20 are raised, no water can enter them, and the machine does not operate to generate gas.

Having thus described the invention, what is claimed is:-

1. In a device of the class described, a tank adapted to contain water; a bell inverted in the tank and extended below the normal level of the water; a carbide container in the bell; a receptacle carried by the tank exteriorly of the bell, the receptacle being submerged at its lower end, and communicating at its lower end with the tank

for the return of water thereto; an exhaust pipe leading from the upper end of the receptacle; a pressure release conduit extended upwardly at one end into the bell to a point below the normal level of the water, and extended upwardly at its other end into the receptacle; and a service outlet communicating with the bell.

2. In a device of the class described, a tank adapted to contain water; a bell inverted in the tank and extended below the normal level of the water; a carbide container in the bell; a receptacle carried by the tank exteriorly of the bell, the receptacle being of conical form and being submerged at its wider lower end, said end of the receptacle communicating with the tank for the return of water thereto; an exhaust pipe leading from the smaller upper end of the receptacle; a pressure release conduit having ends, one of which extends upwardly within the bell to a point below the normal level of the water, the other of said ends extending upwardly within the receptacle, the last specified end of the conduit terminating in a depending bend; and a service outlet communicating with the bell.

3. In a device of the class described, a tank adapted to contain water; a bell inverted in the tank and extended below the normal level of the water; a carbide container in the bell; a receptacle carried by the tank and located between the bell and the tank, the receptacle being submerged at its lower end and communicating through its lower end with the tank for the return of water thereto; an exhaust pipe communicating with the upper end of the receptacle; a pressure release conduit having ends, one of which extends upwardly within the bell to a point below the normal level of the water, the other of said ends extending upwardly within the receptacle; a service pipe communicating with the bell and communicating with the exhaust pipe; and a valve controlling the flow from the service pipe to the exhaust pipe.

In testimony that I claim the foregoing as my own, I have hereto affixed my signature in the presence of two witnesses.

JOHN K. HAWKINS.
